(57) CLAIM

The ornamental design for an accessory for a communication device, as shown and described.

DESCRIPTION

FIG. 1 is a front perspective view of an accessory for a communication device showing my new design;

FIG. 2 is a front elevation thereof;

FIG. 3 is a rear elevation thereof;

FIG. 4 is a top plan view thereof;

FIG. 5 is a bottom plan view thereof;

FIG. 6 is a right side elevation thereof; and,

FIG. 7 is a left side elevation thereof.

The broken lines shown in FIGS. 1-7 are included for the purpose of illustrating environmental elements only and form no part of the claimed design.
